[57] CLAIM

The ornamental design for a rotary card holder, as shown and described.

DESCRIPTION

FIG. 1 is a perspective view of a rotary card holder showing my new design;

FIG. 2 is a side elevational view thereof with the upper portion of the design rotated slightly, the side opposite being substantially a mirror image;

FIG. 3 is a top plan view thereof; and,

FIG. 4 is a bottom plan view thereof.

The broken lines shown in FIGS. 1 and 2 represent environment only and form no part of the claimed design.

FIG. 1

FIG. 2

FIG. 3

FIG. 4
